[57] ABSTRACT

Plain single Jersey stitches are first formed, in accordance with a predetermined Jacquard pattern, with yarn of a first color with cylinder needles, then with dial needles, the yarn being supplied to respective needles alternately when the needles are in knitting position, selected needles (in accordance with the pattern) of the dial, (or cylinder) being disabled when pattern selected cylinder (or dial) needles are knitting; then the needles of the dial (or cylinder) are caused to knit with yarn of a different color, the previously knitting needles being disabled; the yarns of the first and second colors are interknitted at crossover points by transferring yarn of one color from the needle of one group (i.e., cylinder) to needles of the opposite group (i.e., dial), and vice versa. A pair of similar Jacquard pattern controllers are located, in radial alignment, in such a manner that one controller selects the cylinder needles and the other the dial needles simultaneously, the needles of the dial and cylinder being, in accordance with the pattern, brought to knitting position alternatingly.

KNITTING MACHINE FOR KNITTING DOUBLE FACE JACQUARD PATTERN MATERIAL

The present invention relates to a method to manufacture double-sided, patterned tubular Jacquard knitwear with multifeed circular knitting machines, and particularly with machines having a fine cut; and further to apparatus and a pattern arrangement to carry out the method.

It is known to manufacture double-faced patterned flat knit material on flat bed knitting machines, using a patterning arrangement for each needle row, by means of Jacquard cards or on eight-lock machines. Various needle or jack selector groups are arranged in accordance with a pattern to guide the needles to produce reversible patterned knitted material.

Circular knitting machinery having apparatus to select the dial needles have been proposed and are described in the literature (see, for example, British Patents 311,898; 734,406; U.S. Pat. Nos. 2,697,336, 2,814,937; German Patent 668,048; 444,989; and 1,186,972, which corresponds to British Patent 874,719). Single-faced patterns on the inner side of the knit material can be made by such machines, by selecting the dial needle in accordance with predetermined patterns.

Circular knitting machines having various types of needles and of various needle length are also known, in order to manufacture vertically striped material, for example similar to the eight-lock, flat bed knitting machines, such as eight-lock circular knitting machinery. Such machines to select the dial needles in the past could only select the needles of the dial in accordance with a pattern, and took up substantial space, so that the amount of feed of the machinery was reduced, and the repeat height of the pattern was limited. Further, such known patterning arrangements were not suitable to manufacture reversible double-sided patterned Jacquard material, since the pattern wheels for the dial needles, or the index rings therefor could not be separately adjusted for synchronism with the cylinder needle selection arrangement.

It has been found that Jacquard patterns of any selectable pattern could not be made on circular knitting machines having different types of needles, as are customary in machines making long striped patterns.

It is an object of the present invention to provide a method, and an apparatus to carry out the method, to make reversible, that is double-sided patterned Jacquard knit material, or eight-lock knit material on circular knitting machines, so that the result will be similar to the knit material made on flat bed knitting machines, and more particularly to provide a method and apparatus for multifeed circular knitting machines of very fine cut, that is up to the order of 18 or 20 cut/in.

SUBJECT MATTER OF THE PRESENT INVENTION

Briefly, pattern arrangements are provided both for the cylinder needle rows and the dial needle rows. The respective needle rows, or groups, in accordance with the selected pattern, are brought to knitting position with respect to the needles of the oppositely located needle row or group in such a manner that each needle group only makes plain single Jersey stitches, the yarn of one color alternatively forming a portion of the knit pattern. The arrangement provides this sequence: assume selected needles of the cylinder group are knitting with yarn of a first color, e.g., red, forming a first portion of the pattern; the corresponding needles of the dial group do not knit; the red yarn is then switched over to selected needles of the dial to form a second portion of the pattern; during knitting by the selected needles of the dial, the needles of the cylinder group opposite the knitting dial needles are then idle. The missing loops are knitted at a subsequent (with respect to the rotation of the circular knitting machine) knitting feed, with yarn of a different color, e.g., blue. Both sides of the goods are interknitted at the points of crossover, where the yarn of a first color (red) switches over from, for example, the dial needles to the cylinder needles and the yarn of the second color (blue) switches over from the cylinder needles to the dial needles and so on, so that the yarns will complement each other. At knitted regions where the yarns do not cross, that is

where there is no crossover, the material will be double faced and tubular.

Patterns having three or more colors can readily be made by laying floats between the two inner faces of the knit material where it is tubular, the additional yarn forming the floats providing additional knit loops on one or both sides of the final knit material.

The sequence of the feed determines the sequence of the pattern rows, so that selection of the pattern and adjustment of the pattern arrangement may be carried out in known manner as customary with any Jacquard machine.

The apparatus, in accordance with the present invention, provides a pattern arrangement for each knitting feed by means of a Jacquard pattern controller which, by and itself, may be known. Jacquard pattern devices are, in accordance with the invention, located to be radially aligned, so that one pattern device selects the cylinder needles, while another one selected, simultaneously, the dial needles; the needles of the cylinder and of the dial are then, in accordance with the pattern, brought to knitting position alternately, so that the needles of the dial or of the cylinder will be knitting.

The cylinder needles may be selected by any known selector mechanism. For a very fine cut, a special selection mechanism is necessary for the dial needle in order to enable such selection with minimum space requirement. The selector mechanism engages into the tricks for the dial needles and, by means of adjustable or switchable pattern carriers, linkage bars are operated which transfer the pattern command to the dial needles while requiring only little space, the entire arrangement being located in the interior of the dial, where is can be accommodated in spite of the decreasing separation between needle elements due to the radial convergence of the tricks.

The Jacquard control devices for the cylinder, as well as for the dial needles are aligned in radial direction in such a manner that the selected needles of both the cylinder needles and the dial needles commence knitting at the same point of the feed. Those needles and the selector jacks which are not selected remain in their starting position within the cams, so that they can be selected at a subsequent feed; the needles which are knitting, and their associated selector jacks, are brought back to the selecting, that is starting position automatically in advance of reaching the radial position for selection. This arrangement, which is also used for the dial needles, saves so much space that the number of the knitting positions or knitting feeds, as well as the number of the pattern selectors at the circumference of the machine can be increased substantially.

Increase of the number of knitting position results in a larger pattern height, and the possibility to make multicolored patterns of substantial pattern height by pattern selectors which are set manually. In order to further increase the pattern height, pattern carriers, as known, may be used which, after each revolution of the machine, index in accordance with the pattern in such a manner that the pattern presents continuity.

Reversible, double-sided patterned Jacquard knit material has a soft hand, and is light because it has no accumulation of stitches on one side of the material, as is the case with single-faced Jacquard patterns. The production on multifeed systems is high and many varied patterns may readily be selected simply and inexpensively. Since the formation of the knit loops occurs alternately on one group of needles or the other, heavier as well as very thin yarns may be knitted without faults or errors.

The drawings illustrate the method to make a double-sided patterned Jacquard material in accordance with a predetermined pattern, in schematic form. The pattern arrangement is illustrated only with respect to the selection of the dial needles, a pair of different selection arrangements for the same knitting step being illustrated. In the accompanying drawings:

FIG. 1 is a side view of a latch needle, and a selector butt, having 13 selection positions;

FIG. 2 is a schematic top view of the cam track and a conventional selection arrangement for the dial;

FIG. 3 is a fragmentary cross-sectional view of the dial illustrating the selection arrangement for swingably mounted selector jacks for the dial needle, which are located in a cylindrical element, the selector jacks extending at their lower end beneath the needle jacks in the needle slots, or tricks, of the dial;

FIG. 3a is a schematic view of a selection arrangement for dial and cylinder needles;

FIG. 4 is a top view of the cam of the dial, in schematic showing, by which all needle jacks and needle selector jacks are automatically returned in their rest position from which they can be further selected,

FIGS. 5 and 6 are schematic showings of a pattern arrangement made in accordance with the method of the invention, to produce a two-color step pattern on both sides of the fabric knitted on a 36-feed Jacquard circular knitting machine; and

FIGS. 7, 8 and 9 illustrate schematically loop formations of fabric made in accordance with the invention.

FIG. 5 illustrates knitting by one row of needles and FIG. 6 knitting by the other row of needles. Yarn loops appearing at the crossed positions are knitted by needles of one row, e.g., the dial, while yarn loops appearing at the blank positions are knitted by needles of the other row, that is, the cylinder. The crossed fields of FIG. 5 illustrate the loops of one color (e.g., red) of the knit pattern on one side, e.g., the outer side, of the fabric knitted by needles of one row e.g., the dial. At the inner side of the fabric, the yarn of the same color (red) will appear at the position of the blank squares of FIG. 6 knitted by needles of the other row, the cylinder. A different color (e.g., blue), at the outer side, will be knitted by dial needles and will appear at the crossed squares of FIG. 6; and the inner side, the different color (blue) is represented by the blank squares of FIG. 5.

FIG. 7 illustrates the loop arrangement for a two-color patterned fabric; FIG. 8 for a three-color patterned fabric with floats between knitted loops, the third color (marked "green") being double knit at adjacent needles; and FIG. 9 illustrates the loops for a three-color patterned fabric in which yarns of all three colors are floated and the stitch sequence is randomly selected.

Referring now to the drawings, and particularly to the embodiments of FIGS. 1 and 2: The dial is provided with needles 20 and jacks 21 (FIG. 1). Needle 20 has a butt 16. Likewise, Jack 21 has a butt 15 and a group of selector butts 1 to 13. An auxiliary butt 14 is provided at the end. Auxiliary butt 14 secures jack 21 against sliding towards the center of the machinery by bearing against guide ring 22 on the dial 40 (FIG. 2). Needle 20 is placed into knitting position by means of jack 21. The cam track 33 on cam 30 serves as a guide for butt 16 of needle 20. Surface 31 of the cam 30, and transfer part 32 returns the needle to rest position. Each one of the jacks 21 is supplied with a selector butt in such a manner that it can be selected, in staggered arrangement, in from one to 13 positions, in accordance with one to 13 adjacent slots in the dial (FIG. 2).

The machine can be arranged in the usual manner to form symmetrical patterns, V set ups for random patterns, for diagonal patterns, and may have butt arrangements in the needle beds as is well known in connection with circular Jacquard knitting machines.

The plan view, from the bottom, of the cam illustrates the camming tracks associated with the butts on the selector jack. The notation chosen is such that any numbered butt, for example 9, corresponds to a selector track, for example No. 9. A position that is to be selected is given the notation A, and a nonselected butt the notation D.

A box containing 12 or 13 sliders is located in the region of the selector butts above the dial, the box containing replaceable selector jack raising cams, as well as selector jack holding cams, which prevent raising. In the particular example shown in FIG. 2, tracks 1, 7, 8, 9 and 11 are to be selected, as illus-

trated at 1A, 7A, 8A, 9A and 11A; the selector jack back holding cams, preventing raising, are illustrated at positions 2, 3, 4, 5, 6, 10, 12 and 13 by elements 2D, 3D, 4D, 5D, 6D, 10D, 12D and 13D. FIG. 2 illustrates a manual setting, but the selector jack raising cams (corresponding to position A), or back holding cams (position D) could be swiveled under a Jacquard pattern control to assume selectively, as desired, the positions A or D.

The butt 15 of all the jacks is carried by means of cams 24, 25 at position 23 in its exact butt channel, so long as the butts of the jacks 21 are guided by the selector jack back holding cams D. If a selector jack does not have a butt which matches one of the raising cams, butt 15 will remain in the circular track of the dial, thus also keeping the needles within the circular track and not moving them into knitting position. If a butt 15 is to be moved into knitting position, a selector jack raising cam must be placed in a track to engage a projecting selector butt 1 to 13.

Referring again to FIG. 2: selector jack raising cam 9A will engage selector butt 9 on jack 21, to move butt 15 over the point 26 of camming part 27. Point 26 of part 27 engages butt 15 as soon as the selector jack raising cam 9A engages selector butt 9 of the jack. The jack is then carried by part 27 past cam portion 28 so that the selector jack can drive the needle 20 to the knitting position. Jack and needle are then returned by the cam tracks in well-known manner. A nonselected jack, for example one having a selector butt at position 10 is retained by the selector jack back holding cam 10D and pulled back slightly into the machine, until butt 15 is below and behind point 26 of portion 27. The nonoperating jack is then pulled back further by locking part 27, and brought back into position to be selected again if desired, at a further position at point 29, together with those jacks which have been selected and returned. To prevent excessive motion towards the interior of the machine, or drift, auxiliary butt 14 will bear against ring 22 on the dial. Cam parts 24, 25, acting on butt 15 collect the jacks for further operation.

Referring now to FIG. 3 which is a fragmentary cross section of the dial, showing a needle 50 in its trick: selector jacks 53 are located in grooves in a cylindrical structure 70 behind the dial needle 50, the selector jacks 53 selecting the dial needles 50 in accordance with a predetermined pattern. The arrangement in accordance with present invention differs from that of FIGS. 1 and 2 in that an auxiliary selector jack 51 moves the needle jack 54 by means of a small swinging movement over bearing axis 52 in order to introduce the needle jack 54 and its butt into the dial race track. The lower end 53' of the selector jack 51 is placed within the trick for the needle 50 and beneath the needle jack 54, so that positive selection of the needle jack can be obtained even with a very fine cut. In FIG. 3 the needle is shown only schematically.

The selector jacks 51 themselves, which pivot in accordance with a predetermined pattern, are formed with the well-known selector butts as schematically indicated at 51', which can be arranged in staggered location in accordance with the selected pattern, and are operated in known manner by manually settable, or controllable pattern arrangements two setting bars of which are seen at 71, 71'.

Those needle jacks 54 which are lifted enter the cam track, or cam race, so that the needles 50 are brought to knitting position. A means is provided to retain the nonselected needles, needle jacks, and selector jacks in nonoperating position. Those needle jacks 54 which have not been operated, that is which remain depressed within their tricks do not bring needles 50 into knitting position. The needle jacks 54, remaining in the tricks, retain the not selected needles 50 in nonknitting position. Return holding cam 55, having an angled extension 56 (FIG. 4), depresses the needle jacks 54 during their return motion to retain them depressed in the tricks, thereby also causing pivoting of the selector jacks 53, to their rest position. The end of the jack 54 slides over the angled camming extension 56 during the return, in order to slide the jacks and needles back after having been advanced to a knitting position.

FIG. 4 is a detail view of the return holding cam 55. Automatic return positioning of the needle jacks 54 into their rest or nonknitting position while the machine is knitting, and small displacement of the selector jacks during jack selection enables arrangement of the pattern control for the dial needles in a very small and tight space, thus increasing the cut and the number of feed positions, so that cuts in the order of 20 per inch can be obtained.

FIG. 3a shows, in highly schematic form, the dial needle selection of FIG. 3, reversed right for left, in combination with a cylinder needle selection arrangement, also shown schematically, which is generally well known. Selector jacks 57 operate the cylinder needles 150. The number of selector butts for the cylinder jacks, as well as for the dial selector jacks 51 is the same. The only difference is the mode of operation and effect on the needles. The action of the selector cams on the butts is such that when the dial needles are in knitting operation, the cylinder needles are out of operation. The radial alignment of the jacks in the cylinder, as well as the dial needle beds is such that they are in radial registration. Such an arrangement of the selector jacks, and their butts, makes selection of a double-sided pattern very simple, since a similar adjustment of the pattern arrangement for both groups of needles automatically forms a double-sided pattern, as seen, for example, in the schematic diagram for the double-sided patterns of FIGS. 5 and 6.

To make a three-colored pattern, the needles to form the loops of the third color are disabled in the knitting feeds of the yarns of the first and second color. The yarns of the first and second color are laid, in the region of the remaining needles on any knitting feed and not knitted by the needles of the first and second color, as floats between the oppositely connected rows of loops. Then the third color is knitted. The yarn of the third color forms floats between the rows of loops in the region of the first and second colors.

Other arrangements, with different distribution of relative position of the colors and floats are of course possible and will be apparent to those skilled in the art. The various possibilities of forming patterns to make reversible, that is double-faced Jacquard material are similar to those for one-sided patterns. They can be selected separately for each side of the material. The pattern arrangement in accordance with FIG. 3 illustrates pattern selection of pattern controllers 71, 71' by hand, the pattern controllers being locked into working position by 45 suitable locking means. Such an arrangement permits setting of the pattern control to make small designs, the pattern height being determined by the number of knitting positions and the pattern width by the number of selector butts on the selector jacks. To make larger designs, the pattern selectors 50 may be operated in known manners, using pattern carriers

which can be indexed or switched. Of course, needle jacks with larger numbers of butts may also be used.

The present invention has been illustrated largely in schematic form, the structure of the entire knitting machine, the operation and the method of yarn feed being well known and standard in the art; reference may be had to the patents aforementioned, and for a description of complete machines to various textbooks in the field, and for example, "Knitted Outerwear Times", for example Vol. 35, No. 19 (May 5, 1966) or Vol. 36, No. 20, (May 8, 1967), in which various knitting terms are defined and machines described in detail.

We claim:

1. Knitting arrangement in a circular knitting machine having a dial, a cylinder, needles located in dial and cylinder needle rows, a plurality of knitting feeds, arranged around said dial and cylinder, and Jacquard-type pattern means controlling operation of the needles of the feeds in the dial and in the cylinder in accordance with a preselected Jacquard pattern;

said Jacquard-type pattern means comprising a pair of similar Jacquard-type pattern controllers at a feed, one each being associated with the dial needle row and the other with the cylinder needle row, respectively, said pattern controllers being located with respect to each other in radially aligned position, and located with respect to the dial and cylinder needles for simultaneous selection of respective dial and cylinder needles;

said Jacquard-type pattern controllers alternatingly activating to knitting position selected needles first of one of said rows only, and then of the other of said rows only, to control knitting operation of the needles of said rows alternatingly and in accordance with a selected pattern; including slots formed in the dial;

needle jacks; and
selector jacks,

said needles located in said dial needle row being in said slots, the selector jacks being engageable by the Jacquard-type pattern controllers, and the selector jacks and needle jacks being guided in said slots;

each said needle jack being pivotally mounted on an associated needle for swinging movement, one of said Jacquard-type pattern controllers selectively operating selector jacks to cause swinging movement of needle jacks to move associated needles to knitting position.

2. Knitting machine according to claim 1, wherein the selector jacks each have an operating end located in a slot and engaging a needle jack;

and guide means returning selected and previously knitting needles and needle jacks and selector jacks to rest position in advance of reaching a further selection position.
